(57) **CLAIM**

I claim the ornamental design for the water dumping container, as shown and described.

DESCRIPTION

FIG. 1 is a back side view of the water dumping container. FIG. 2 is a front side view of the water dumping container. FIG. 3 is a right side view of the water dumping container. FIG. 4 is a left side view of the water dumping container. FIG. 5 is a top view of the water dumping container; and, FIG. 6 is bottom view of the water dumping container. The broken line showing of indicia is included for the purpose of illustrating environment and forms no part of the claimed design.
